UNITED STATES PATENT OFFICE.

ROSWELL A. MOORE, JR., OF KENSINGTON, CONNECTICUT, ASSIGNOR TO
MAURICE SCHEUER AND CHARLES SCHEUER, OF NEW YORK, N. Y.

TAPE GUIDE AND FASTENER.

SPECIFICATION forming part of Letters Patent No. 727,551, dated May 5, 1903.

Application filed February 17, 1903. Serial No. 143,796. (No model.)

To all whom it may concern:

Be it known that I, ROSWELL A. MOORE, Jr., a citizen of the United States, residing at Kensington, in the county of Hartford and State of Connecticut, have invented certain new and useful Improvements in Tape Guides and Fasteners, of which the following is a specification.

My invention relates to an improved tape guide and fastener for supporting various devices from a loop around the wearer's body; and the objects of my improvement are simplicity and economy in construction and convenience and efficiency in use.

In the accompanying drawings, Figure 1 is a front elevation of my guide and fastener, together with a tape arranged in loop form, with its end portions threaded through the said guides and provided with an ordinary form of hose-supporters. Fig. 2 is a front elevation of the two members of my guide and fastener slightly separated from each other. Fig. 3 is a like view of the same with the two members brought toward each other ready for engaging the fastening devices to connect the said members together. Fig. 4 is a plan view of the right-hand member of Figs. 2 and 3. Fig. 5 is a front view of a portion of one member in a modified form.

D designates a tape, strap, or belt of any suitable material, but which for convenience of description I will hereinafter refer to as a "tape."

B and C designate the two members of my guide and fastener, and D designates an ordinary form of hose-supporters.

The member B is essentially the stud member of my guide and fastener and is formed of a plate 5, a headed stud 6, and a wire frame having three eyes 7 8 8, the ends of the wire being secured within a rolled edge 9 of the plate 5. The eye 7 extends lengthwise with the rolled edge of the plate 5, and the other two eyes 8 8 extend away from the said edge and preferably on outwardly-converging lines. These eyes are formed from a single piece of wire. Beginning at the upper end of the plate 5, in Fig. 2, the wire is bent at an angle to the rolled edge of the said plate, then doubled upon itself to form the outer end of the upper eye 8, then bent again

to form the opposite end of the said eye and to carry the wire in front of the lower member of the said eye and slightly away from the rolled edge 9, then bent to carry it along by the side of the said rolled edge, leaving an offset 10 near the junction of the upper eye 8 with the upper end of the eye 7, then bent to form a like offset 10 at the lower end of the eye 7, and then outwardly and backwardly, so as to again double the wire upon itself to form the lower one of the eyes 8 8, and then bending it to bring the end of the wire up into the rolled edge 9. The metal plate 5 is provided with an ear 11 and the headed stud 6, before referred to, the said ear, as shown, having a peculiar slot therein, which may be described as a T-shaped slot with the upright curved toward the wire frame in a zig-zag curve.

The member C has the same wire frame, with eyes 7 8 8, as in the member B the metal plate 5 being also the same only it has no headed stud. The slot in the member B is for hooking the guide to a headed stud on the corset of the wearer, while the slot in the member C is for engaging the headed stud 6 of the member B to connect the said two members, as shown in Fig. 1. It may, however, be used, if desired, to hook upon the headed stud of the corset, in which case the two members B and C would be connected by hooking them both upon the corset-stud.

The slots in the ears comprise a retaining-pocket 12, extending longitudinally in the line of a pull that would tend to separate the two members B C, and an entering-slot 13 of a curved zigzag form, that extends transversely to the said retaining-pocket and inclines backwardly from its junction with the said retaining-slot to the edge of the plate. I prefer to make this slot with the retaining-pocket 12 extending in both directions from its junction with the entering-slot 13, as shown in Figs. 1, 2, and 3, because when so made there is less liability of accidental unfastening; otherwise the retaining-pocket 12^a of Fig. 5 has the same mode of action. In order to connect the two members B and C, the member C is brought into position in front of the member B and the edge of the metal plate 5 of the member C placed against

the body of the stud under its head, as shown in Fig. 3. Then the member C is pushed downwardly and away from the member B, and the stud will readily draw into the retaining-pocket 12 as the member C moves obliquely down into place, as shown in Fig. 1.

I have shown the tape as having its end portions carry an ordinary form of hose-support; but it is evident that the particular article, garment, or appendage carried by these ends is wholly immaterial. The tape, as shown in Fig. 1, is threaded through the guide by first passing one end through the upper eye of the left-hand member from the rear, then through the longer eye 7 from the front, then turning the tape on itself and through the lower eye from the rear and then downwardly to whatever the tape may support, then passing the other end of the tape through the upper eye of the other member, and then through the longer eye from the rear and down through the lower eye, as in the left-hand member.

By my improvement the guides are skeletonized, so as to be very light. They are also flexible through the rolled edge that forms a joint between the metal plate and the wire frame, while the wire frame itself is resilient, thereby making the guides more comfortable to the wearer. The eyes being formed of wire have a good smooth surface, so that the tape more readily slides therethrough, and the guides adjust themselves to the various positions of the wearer. The particular form of slot in the fastening-ear enables the guides to direct the stud into its retaining-pocket.

I claim as my invention—

1. A guide and fastener, consisting of two members, each member comprising the fastening-plate and the wire frame with its three eyes to receive the tape, substantially as described.

2. A guide and fastener consisting of two members, each member comprising the fastening-plate and the wire frame with the wire

twice doubled upon itself to form the eyes 8, 8, with an intermediate portion and ends of the wire connected with the said plate and forming the eye 7, substantially as described.

3. A guide and fastener consisting of two members, each member comprising the fastening-plate and the wire frame with three eyes connected to the said plate, and having the wire cross itself on front and rear sides at the junction of the said three eyes. 55

4. A guide and fastener consisting of two members, each member comprising the fastening-plate and wire frame having the three eyes, with the member of the middle eye on that side which is farthest from the said plate, 60 offset at each end thereof, substantially as described.

5. In a guide and fastener, the combination of a headed stud with another member having a plate provided with an elongated retaining-pocket extending longitudinally in the line of the pull on the parts, and having an entering-slot extending from the said retaining-pocket transversely backward and outward in a curved zigzag course to the edge of the 70 said plate. 65

6. In a guide and fastener, the combination of a headed stud with another member having a plate provided with a T-shaped slot, the top of the T forming a retaining-pocket 75 that extends longitudinally in the line of the pull on the parts, and the upright of the T forming an entering-slot extending backwardly from the middle portion of the retaining-pocket in a curved zigzag course to the 80 edge of the said plate.

7. In a guide and fastener, a member thereof consisting of the fastening-plate and the wire frame with its three eyes to receive the tape, substantially as described.

R. A. MOORE, JR.
